UNITED STATES PATENT OFFICE.

JOHN E. BELL, OF BROOKLYN, NEW YORK.

MARINE BOILER.

1,303,758.

Specification of Letters Patent. Patented May 13, 1919.

Application filed March 1, 1918. Serial No. 219,924.

To all whom it may concern:

Be it known that I, JOHN E. BELL, a citizen of the United States residing at Brooklyn, county of Kings, and State of New York, have invented certain new and useful Improvements in Marine Boilers, of which the following is a full, clear, and exact description.

The objects which I have primarily in view in the designing and construction of the marine boiler, upon which this application for Letters Patent is based, were to produce such a structure at greatly reduced cost, to avoid all complications in its design, so as to bring its manufacture within the scope of the facilities of ordinary makers of such apparatus, and to increase to the utmost possible limit its practical value and efficiency.

I have therefore devised such a boiler in the form which I have illustrated in the accompanying drawings. It is one that cannot claim distinction from existing forms, except in certain particulars, along very radically new lines, but which is characterized by improvements, mainly in details of construction and mode of operation with regard to which no broad statement of their nature and purpose will serve any useful purpose in indicating those features of patentable novelty which it embodies and involves. I shall therefore describe my improvements somewhat specifically, by reference to the accompanying drawings, pointing out, as convenient opportunity presents, those novel features which constitute a departure from preexisting forms.

Figure 1 is a view in front elevation of a complete marine boiler and casing constructed in accordance with my invention.

Fig. 2 is a view in elevation of one side of the boiler, with parts of the casing removed to exhibit the relations thereof of a superheater.

Fig. 3 is an enlarged view in elevation of a portion of the casing illustrating details of construction entering into the same.

Fig. 4 is an enlarged sectional view of a part of the casing and parts of the interior or boiler proper.

Fig. 5 is a vertical cross-sectional view of the complete structure.

Fig. 6 is a similar cross-sectional view but at right angles to the plane of Fig. 5.

Fig. 7 is an enlarged sectional view of a detail entering into the construction of one of the boiler headers.

Fig. 8 is a part horizontal section and part top plan view mainly of the boiler proper.

Fig. 9 is a part elevation and part cross-section of the portion of the boiler at one end of the tubes, to show the disposition of the latter, with reference to each other and to certain hollow bolts through the headers, by the use of which the tubes are cleaned.

Fig. 10 is a detail of a modified arrangement of the tubes and stay bolts.

For a general understanding of the construction of the boiler as a whole reference may be had to Fig. 6. This boiler is provided with a proper setting 1, the walls being built up in any suitable manner, and is placed over a fire box 2, also of the usual character. The boiler proper is composed of two continuous box shaped headers 3 and 4, connected by straight tubes 5, inclined forward at an angle of 18° to the horizontal.

The steam and water drum 6, is connected by nipples 7, with the front header 3, and by circulation tubes 8, with the rear header, which last named tubes are in two rows, expanded into the drum above and below the center line respectively, and at the other end slightly bent so as to enter the rear header normally.

Opposite each boiler tube 5, and in the outer plates of the headers 3, are hand holes with slightly beveled sides, which are closed by conical plugs 9, and drawn by nuts 11, with a force that presses a soft metal seat or gasket with which these devices are usually furnished to the shape of the opening and prevents further advance of the plugs.

The header plates 13 and 14, as shown in Figs. 6 and 7, are connected by hollow stay bolts 12, and every other tube 5 is left out of the second row and every other alternate row, as shown in Fig. 5, opposite the points occupied by the stay bolts. By this means each hollow stay bolt is at the center of a cluster of six boiler tubes, and affords a very effective and convenient means for cleaning or dusting the tubes, by the introduction of a steam or air lance 15, through said bolts as indicated in Fig. 7.

The boiler tubes in the several rows are spaced close together so that the gas velocity is high and little baffling is required. It will also be observed that the streams of hot gas passing between the tubes of the closely spaced rows expand and mix before they impinge directly upon the tubes in the next succeeding row owing to the position of the

widely spaced tubes, while each close spaced tube is almost directly in the path of the gases passing through the spaces between them and the widely spaced tubes below, 5 and this is a matter of prime importance and adds greatly to the efficiency of the boiler. It is not essential to this special feature of the improvement that the exact disposition of the boiler tubes illustrated should be followed, 10 as other arrangements such as shown in Fig. 10 possess the same or similar advantages. In this Fig. 10 the boiler tubes 5 are disposed in double rows, spaced so as to admit of stay bolts between each two rows. 15 The tubes of one row of each pair are placed opposite spaces in the accompanying row, and the stay bolts occupy a like relative position to the tubes of adjacent rows. By this arrangement the same provision for cleaning 20 the boiler tubes is afforded.

The tube arrangement described, in effect, consists of a number of screens formed by closely spacing the tubes with open spaces between them. The gases of combustion pass 25 through the tube screens at high velocity and the temperature gradient along the sides of the tubes is that usually met with in boilers of the cross-pass type. In the open spaces the gas streams intermingle, due to the creation 30 of eddies and the lowering of the velocity of flow so that the temperature gradient is destroyed and the gases are at a uniform temperature and contact with the next succeeding row with this uniform temperature 35 established. Thus a very steep temperature gradient acts on the lower sides of the tubes, or the points of first contact, which results in a more rapid transfer of heat than is obtainable from a uniform flow 40 with the attendant temperature gradient. The difference between the ordinary and this new means of heat transmission is somewhat analogous to the action in mechanics of an ordinary force and forces due to impacts.

45 The boiler is supported by lugs 16 riveted to the sides of the headers near the bottom as shown in Figs. 3 and 4. These lugs 16 rest in cradles 17 carried by the box like casing 18 which surrounds the furnace. The 50 boiler proper is surrounded by and inclosed in a casing 19 which is bolted to pads 20 riveted to the headers so that the boiler and its casing form a single rigid structure.

This construction has many important advantages. The casing is very materially stiffened so that no cross bracing which, under ordinary circumstances is necessary, is required. The casing is completed by the addition of two inches of suitable heat insulator 21 and two inches of fire brick 22 around the tubes, while that portion of the casing which surrounds the furnace is lined with three inches of insulation 23 and nine inches of fire brick 24.

65 At about the center of the bank of tubes

5 an open space is left to permit the installation of a superheater 24, the tubes of which run at right angles to those of the boiler. Under this superheater there is a baffle 26, Fig. 6, and above it at front and back are 70 two short baffles 27 and 28. These baffles together with a plate baffle 29 over the top of the bank of boiler tubes, with openings at front and rear, as shown in Fig. 6, and two tile deflectors 30, immediately above the 75 bottom row of boiler tubes direct the hot gases in a sinuous path through the bank of tubes, the direction of travel, in the main, being at right angles to all the tubes.

With the remaining structural details 80 this application is not especially concerned. It may be stated that the casing is provided with the usual and necessary doors for inspecting the superheater or for gaining access to the interior of the furnace; that any 85 proper means may be used for opening, closing or securing such doors; that provision may be made for burning either coal or oil under the boiler, and that the plan of pipe connections between the boiler tubes, 90 drums and superheater may be such as is ordinarily employed or as necessity may require.

It remains therefore to point out more 95 fully the nature and purpose of the more strikingly novel features which the invention involves, preëminent among which is the tube spacing. Primarily the omission of every other tube in every other row is of great advantage because the vacant spaces 100 may be occupied by the hollow stay bolts. This enables me to space the boiler tubes as closely together as the metal in the end plates or headers permits, with the result of greatly increased efficiency and a marked reduction in the space occupied by a boiler of given capacity. It would be impossible to get a steam lance into the boiler from either side with this close spacing of the tubes, but the close tube spacing together with the stay 105 bolts affords a ready means of cleaning.

There is a peculiar and marked advantage secured by the special system of baffling, which is of such a character that the gases are forced to pass over all portions of the heating surfaces while at the same time the retarding effect on the draft is reduced to a minimum. The baffling used naturally leads to the location of the superheater in the position shown. It will moreover be observed 115 that on either side of this superheater is a space constituting a secondary combustion chamber in which the gases have a chance to mix before passing over the superheater tubes. This feature is of great importance 120 in a marine boiler where the volume of the furnace is limited. As carbon monoxid gas at higher rates of driving enters the tube bank and further combustion is prevented 125 unless the gas can stream into a chamber 130

such as is provided for in this design on both sides of the superheater. In the absence of secondary combustion chambers of this sort, flaming occurs in the uptake and the efficiency of the boiler is reduced. Furthermore, these open spaces establish a uniform temperature in the gases so that they contact with the superheater tubes with a steep temperature gradient. The gases enter the superheater from two sides and at right angles to the tubes so that when the surface of the tubes is composed of Foster rings, or corrugated, it will be thoroughly and effectively swept by such gases.

10 The feature of attaching the casing solidly to the headers of the boiler is also of importance as the headers constitute girders of the greatest stiffness whereby a very rigid casing is afforded with the minimum of space.

15 The special arrangement and close spacing of the boiler tubes, it may be further stated, has certain peculiar advantages. It is well known that the rate at which heat is absorbed from a hot gas by a cooler surface, is almost directly proportional to the velocity of the gas over that surface, or more strictly speaking, to the product of the velocity and the density, or what is known as 20 the "mass flow". To secure this high velocity it has been customary to insert in boilers baffles which have a tendency to increase the length of the path of gases from the furnace to the gas outlet. It has, moreover, been demonstrated by experiment that when the gas passes over the tubes in a direction at right angles to their axes the absorption of heat is at a greater rate for a given velocity than when the gas travels 25 along the tubes, as a result in the most efficient form of boiler the baffles are arranged to secure a transverse passage of the gases, but this usually involves the forcing of the gas to make two or three complete and abrupt turns and is accompanied by a loss of 30 draft. If this loss be too high the capacity of the boiler is reduced, so that the ideal ar-

rangements of baffling is that which gives the maximum of heat absorption with the minimum of draft loss.

50

In the boiler herein shown and described a high velocity of gas travel is secured by spacing the boiler tubes close together rather than through the baffle arrangement. The turns in the gas path around the baffles are 55 not sharp, so that the draft loss is low and in the main the gases travel across the tubes and not along them.

60

Having now described my invention, what I claim is:

1. A marine boiler comprising a bank of straight tubes, continuous headers joined thereby, and a casing surrounding the tubes and headers rigidly secured to the headers.

65

2. A marine boiler comprising a bank of straight tubes, continuous box like headers joined thereby, and a covering or casing surrounding the tubes and headers and rigidly secured to the headers.

70

3. A marine boiler comprising a bank of straight tubes, continuous headers joined thereby, a casing surrounding the tubes and headers and rigidly secured to the headers, and supports for the boiler formed by lugs secured to the headers near their lower ends, 75 and cradles attached to the metal casing in which said lugs rest.

75

4. A marine boiler comprising a bank of tubes, continuous headers joined thereby and arranged above the furnace, a metal casing 80 surrounding the furnace, a metal casing surrounding the tubes and rigidly secured to the headers, and supported upon or by the furnace casing, and heat insulating linings for both casings.

85

5. A marine boiler comprising a bank of tubes, headers joined thereby and arranged above the furnace, a metal casing surrounding the furnace connected at its four corners by lugs to the headers.

90

In testimony whereof I hereunto affix my signature.

JOHN E. BELL.
